US0D1020426S

(12) **United States Design Patent** (10) Patent No.: **US D1,020,426 S**
(45) Date of Patent: ** *Apr. 2, 2024

(54) **KNIFE**

(71) Applicant: **Outdoor Edge Cutlery, LLC**, Denver, CO (US)

(72) Inventor: **David R. Bloch**, Boulder, CO (US)

(73) Assignee: **OUTDOOR EDGE CUTLERY, LLC**, Denver, CO (US)

(*) Notice: This patent is subject to a terminal disclaimer.

(**) Term: **15 Years**

(21) Appl. No.: **29/834,835**

(22) Filed: **Apr. 14, 2022**

(57) **CLAIM**

The ornamental design for a knife, as shown and described.

DESCRIPTION

FIG. 1 is a front view of a knife showing my new design; FIG. 2 is a front view of the knife with the blade removed; FIG. 3 is a perspective front view of the knife; FIG. 4 is a perspective front view of the knife with the blade partially removed; FIG. 5 is a front view of the knife, wherein the broken line matter is modified; FIG. 6 is a front view of the knife with the modified broken line matter, wherein the blade is partly removed; and, FIG. 7 a perspective view of the knife with the modified broken line matter. The broken lines depict parts of the knife that form no part of the claimed design.

1 Claim, 4 Drawing Sheets

Related U.S. Application Data

continuation-in-part of application No. 14/063,333, filed on Oct. 25, 2013, now Pat. No. 9,687,987.
